UNITED STATES PATENT OFFICE.

LYMAN ARNOLD, OF LYNN, MASSACHUSETTS, ASSIGNOR TO GENERAL ELECTRIC COMPANY, A CORPORATION OF NEW YORK.

REGULATING DEVICE.

Application filed November 19, 1917. Serial No. 202,758.

To all whom it may concern:

Be it known that I, LYMAN ARNOLD, a citizen of the United States, residing at Lynn, in the county of Essex, State of Massachusetts, have invented certain new and useful Improvements in Regulating Devices, of which the following is a specification.

My invention relates to movable coil constant current transformers and reactances.

10 Constant current electrical apparatus of this type consist of relatively movable windings and a core providing a magnetic circuit inductively relating the windings. The magnetic repulsion between the windings determines the relative positions of the windings at any instant, and hence controls the current supplied to the load. Heretofore the almost uniform practice has been to suspend the movable windings and any counter-balancing weights there may be, by means of cords or other flexible members.

Some of the objects of my invention are to improve such constant current devices, particularly transformers, rendering them 25 simpler and cheaper, and particularly more rugged, and suitable for mounting outdoors on poles substantially as transformers without moving parts are often mounted. Another advantage of my invention is that a 30 considerable part of the insulation heretofore applied to the coils to insulate the same from the core, may easily be omitted from the coils and applied directly to the core. Since my invention will probably find its 35 greatest application in constant current transformers, I shall hereinafter for the sake of simplicity refer to such transformers substantially entirely; the application of my invention to other devices will be understood therefrom.

40 In order that a constant current transformer (and similar constant current devices) may be mounted outdoors at the top of a pole, it must not only be rugged but it must require but little attention, and must be capable of operating at an appreciable and variable angle to the vertical in any direction. Constant current transformers of the usual construction prior to my invention do not meet these requirements; on the other hand, constant current transformers embodying my invention meet these requirements fully and hence are particularly adapted for outdoor pole mounting; but it 55 should be understood that my invention is

not limited in its application to outdoor pole mounted devices for it may be embodied in constant current transformers installed as constant current transformers are more generally used, in stations having attendants and on firm foundations. In carrying out my invention I provide means for positively guiding the movable windings, holding the movable windings rigidly, mechanically, against movement in all directions except those directions in which the windings should move to control the current.

I am aware that in some constant current transformers movable windings suspended from above by cords, have been provided with devices which to an extent act something like guides to restrain the movements of the coils, for example cooperating grooves and tongues carried directly by the movable windings and the respective winding legs. In such constructions, however, the guides have substantially no function during the normal operation of the transformer, for the friction of such guides is sufficient to render the operation of the device unsatisfactory if the guides are depended upon to actually guide the coils at all times; the coils of such devices are therefore supported in such a way that the cooperating parts of the guides are normally out of engagement with each other, and act only to restrain the movable windings when the repulsion is so uneven or excessive as to tip the coils or drive the coils toward the winding legs. My invention is distinguished from this practice in that the movable coils of my invention are positively guided at all times; the repulsion of the coils acts on the friction of the guiding means as through a lever, with the repulsion at a greater distance from the fulcrum of the lever than the friction whereby the effect of the friction on the regulation of the device is sufficiently nullified. Preferably also the axes of the core legs of the transformer are straight lines. My invention therefore resides principally in the substitution of coil guiding and supporting means of the sort I have indicated, for the coil supporting means of the common prior practice. From another aspect my invention consists in positively guiding both the movable winding or windings and any weight or weights that may be used for controlling the movement of the movable winding, coun-

terbalancing the winding or otherwise, so that the winding and weight continue to operate effectively irrespective of the angular displacement of the transformer from the vertical. My invention and its distinctions from the prior art will be more completely understood from the accompanying drawings and the following description and claims.

10 In the accompanying drawings and the following description I have illustrated and described in some detail the best embodiments of my invention of which I am now aware. Figs. 1 and 2 are two views in elevation of one embodiment of my invention. Fig. 3 illustrates in elevation, partly in section, a preferred embodiment of my invention in a constant current transformer. Fig. 4 is a perspective view of the transformer of Fig. 3. Fig. 5 is a perspective view of another preferred embodiment of my invention. Fig. 6 is an elevation of a modification of the embodiment of my invention of Fig. 4. And Fig. 7 is a perspective view of a quite different form of device embodying my invention.

The core 10 of the transformer of Figs. 1 and 2 is of the three legged type; this type of core is well known and is more clearly illustrated in Fig. 4. The axes of the winding leg 11 and the outer legs 12 of this core 10 are substantially straight lines and are disposed substantially horizontally; yoke members 13 complete the magnetic circuit 30 through the winding leg 11 by joining the ends of this winding leg 11 to the ends of the outer legs 12. The windings, mounted about the middle or winding leg 11, comprise a fixed winding 8 of two coils fixed about and adjacent one end of the winding leg 11, and a movable winding 9 also of two coils, about the other end of the winding leg 11. The coils of the movable winding 9 are spaced apart and fastened rigidly together by the blocks 15 and 16 and bolts 17 and 18. To the upper blocks 16 are rigidly attached two members 19 of a pivoted device which engages with each side of the movable winding 9 such members being pivoted some distance apart along the shaft 21. This device as a whole forms in effect a pivoted support swung from shaft 21 for the winding 9. The shaft 21 is carried above the winding 9 by suitable means here shown as the frame members 22 which are attached to the core clamps 23, the winding 9 depending pendulum-like from the shaft 21. The legs 24 are attached to lower core clamps 23 and thereby the whole transformer is carried. The cross member 25, carried by one of the frames 22, is the terminal board for the transformer; the winding terminals which usually pass through this terminal board have been omitted in order not to complicate the drawing. A threaded rod 28, at-

tached to the shaft 21, carries the weight 29 for controlling the movement of the winding 9; the weight 29 is thus positively guided in its movements. The weight 29 may be moved along the outer end of the rod 28 by rotation on the threads thereof as appears from the drawing; lock nuts 30 secure the weight 29 in any particular position to which it may be moved. The repulsion between the windings 8 and 9 tends to drive the winding 9 to the right in Fig. 1; gravity tends to move the winding 9 to the left or toward the winding 8. The winding 9 moves through an arc of a circle about the center of the shaft 21 as a center; consequently the core opening in the winding 9 must be sufficiently larger than the cross area of the leg 11 to allow this movement.

The operation of the transformer of Figs. 1 and 2 is substantially like the operation of constant current transformers heretofore known: The fixed winding 8 may be either the primary or secondary winding; correspondingly the movable winding 9 is the secondary or primary winding. As the current in the secondary winding tends to increase (by reason for example, of a reduction in the resistance of the secondary circuit due to change in load), the movable winding 9 is repelled to the right (Fig. 1) or away from the fixed winding 8 against the force of gravity; the leakage magnetic flux is thereby increased and the movable winding 9 assumes such a new position that the current in the secondary winding remains substantially unaltered in value. As the current tends to decrease, gravity moves the winding 9 in the opposite direction, toward the winding 8 to maintain the current at substantially a constant value. The friction of the guiding means resides at the periphery of the shaft 21. The repulsion of the windings acts on this friction by means of a lever in effect, the center of the shaft 21 being the fulcrum of the lever; the repulsion or winding arm of the lever is of a length equal, substantially, to the distance from the center of the shaft 21 to the center of the winding 9; the friction arm of the lever is of the same length as the radius of the shaft 21. Hence it is that the friction of the guiding means is without material effect on the regulation of the device. The weight 29 may be moved along the rod 28 to change the value of the current to be maintained in the secondary winding.

It will be observed that this transformer is different from that of the present common practice in that the movable winding 9 is positively guided in its movement by its pivoted arm, and further in that the weight 29, which controls the movement of the movable winding 9, is also positively guided. Consequently the floor or other support for this transformer may depart from the hori-

- zontal (or to say it in another way, the upright axis of the transformer may depart from the vertical) by an appreciable angle in any direction without greatly affecting the operation of the transformer. If the departure is at right angles to the plane of the drawing as the apparatus is represented in Fig. 1, then this departure from the vertical for a number of degrees is substantially without any effect on the operation of the device; if the departure from the vertical is in the plane of the drawing (Fig. 1) it is also without material effect for some displacement, or if the departure becomes sufficient, it may be compensated for by an adjustment of the weight 29 on the rod 28. Furthermore, the scheme of mounting the movable windings just described allows a considerable part of the insulation for insulating the windings from the core to be applied to the core itself instead of to the windings as heretofore; obviously this has numerous advantages. For example it materially reduces the amount of labor required in the construction of the device, for insulating material for the coils must be applied as tape not exceeding about one inch in width (due to curvature of the coils), while much greater widths can be applied to the straight core parts; also the capacity of the apparatus is somewhat increased since the windings are better ventilated and hence may be operated at higher electrical densities.
- 35 Figs. 3 and 4 illustrate a somewhat different and a preferred embodiment of my invention. In Fig. 3 the transformer tank is in section to show the transformer in place therein. The transformer core 40 is laminated as shown and is provided with the core clamps 41 and 42 to hold the laminations in position; these core clamps 41 and 42 are held together by the rods 43. As before, the core 40 is of the three legged type, the windings 44 and 45 being about the middle or winding leg and as before a considerable part of the insulation for insulating the core from the windings is applied directly to the core instead of to the coils. 50 The axis of the winding leg of the core is generally vertical however in the case illustrated in Figs. 3 and 4, and the arm 48 which guides the movable winding 45 is disposed substantially horizontally; this arm is pivoted at 49 to an extension 50 of the core clamp 41. The rod 54 passes loosely through another extension 53 of the core clamp 41. At its lower end this rod 54 is attached to the pivoted arm 48 adjacent the movable winding 45; above the core clamp 60 this rod 54 carries a weight 55 for controlling the movement of the movable winding 45.
- It will be observed that the principal differences between the transformers of Fig. 1 and Fig. 3 are that in the latter the coil bearing arm 48 is substantially horizontal instead of vertical as in the former, and the coil controlling weight 55 moves linearly instead of about a pivot as in the transformer of Fig. 1. As before, the movable winding is positively guided by a pivoted arm to which it is rigidly attached at both sides, and also as before the controlling weight 55 is positively guided in its movements. The structure of Figs. 3 and 4 is even less affected by a departure of its upright axis from the vertical (or the departure of its floor from the horizontal) than the structure of Figs. 1 and 2 as will be apparent.
- The transformer of Fig. 5 principally distinguishes from those heretofore illustrated and described in that all of the windings are movable with respect to the core. As in the case of the transformer of Fig. 3, the core is of the three legged type, the windings being about the middle leg which is substantially vertical. One winding 60 is carried by an arm 61 which is pivoted at 62 at one side of the core. The other winding 64 is carried by a like arm 65 which is pivoted at 66 at the opposite side of the core. The pivots 62 and 66 are so located that each of the windings 60 and 64 may travel from substantially the center of the winding leg to one of the (and opposite) ends thereof. A lever 68 is pivoted between its ends at the top of the core as illustrated; coupling members 69 and 70 couple the opposite ends of this lever 68 to the free ends of the arms 61 and 65 which guide the windings 60 and 64 in their movements. As a consequence of the lever 68 and the coupling members 69 and 70, each repulsion of the windings from each other (or movement of the windings toward each other) results in proportional movements of the two windings. A rod 71 fixes any weight desired at one (or the other) end of the lever to control the movements of the windings toward and from each other.
- This transformer of Fig. 5 operates substantially as do the constant current transformers hereinbefore described except that all of the windings move instead of only part of the windings. In a transformer of this type both the linear and the angular motions are smaller than in a transformer in which only a part of the windings are movable and hence the pivoted arms and the mean length of turn may be shorter (the core opening in the winding not necessarily being so much larger than the core leg cross section).
- The transformer of Fig. 6 is quite similar to that of Fig. 3 except that a lever 75, pivoted between its ends on the shaft 74 carried by the upper core clamp 78, is used for the weight 76 which controls the movement of

the movable coil 77. The weight 76 is carried at the end of the lever 75 toward the pivot through which the winding 77 is guided; the other end of the lever 75 is joined by means of the rod 79 to the free end of the pivoted arm which directs the movement of the winding 77. The operation of this device is similar to that of the transformer of Fig. 3. The principal difference between these two transformers is that the weight 76 counterbalances a part of the weight of the winding 77, while in the structure of Fig. 3 the effect of the weight 55 is added to the weight of its winding 45. In both cases, of course, the weight controls the movement of its winding.

The transformer of Fig. 7 is quite similar to that of Fig. 1 except that the core 80 is curved along an arc, the center of which is substantially the pivot 81 from which the movable winding 82 is guided. The winding 83 is fixed adjacent one end of the core 80. The controlling weight 84 is rigidly carried with the movable winding 82 through the pivot shaft 81. The advantage of the structure of Fig. 7 over that of Fig. 1 is that the opening in the movable winding through which the winding leg of the core passes, may be smaller in the structure of Fig. 7 than in the structure of Fig. 1. It will be apparent that in the structure of Fig. 7, this opening need be only slightly larger than the winding leg. The disadvantage of the structure of Fig. 7 is that it is difficult and expensive, wasteful of labor and generally wasteful of material, to build a core along an arc and to successfully arrange the other parts of the apparatus having such a core.

It will be observed that the arm of each of the devices herein illustrated and described comprises two members rigidly attached to the movable winding, one at each side thereof, and engaging the pivot shaft some distance apart. By thus arranging the arm to grasp the coil at both sides thereof and providing it, in effect, with a long bearing on its pivot, the movable winding is strongly held against tilting. I contemplate, however, that modifications of this arrangement for accomplishing the same result will be found.

While I have described the principle of my invention and the best mode I have contemplated for applying this principle, other modifications will occur to those skilled in this art and I aim in the appended claims to cover all modifications which do not involve a departure from the spirit and scope of my invention.

What I claim as new and desire to secure by Letters Patent of the United States, is:

1. In a constant current electrical apparatus, the combination with a magnetic core

having a substantially rectilinear winding leg and cooperating members forming a window, of a plurality of windings surrounding said leg which traverse the window, one of said windings being adapted to move longitudinally along said leg in response to impulses engendered by the magnetic interaction of the windings, means rigidly secured to said core exteriorly of said window, and a pivoted device swung from said means for supporting said movable winding, said device being proportioned to provide a relatively large radius of swing in comparison with the arc of travel.

2. In a constant current electrical apparatus, the combination specified in claim 1, having the pivoted device axially supported at a plurality of points spaced apart.

3. In a constant current electrical apparatus, the combination specified in claim 1, having the pivoted device axially supported at a plurality of points spaced apart, said device engaging with the movable winding at each side thereof.

4. In a constant current electrical apparatus, the combination with a core having a winding leg the axis of which is substantially a straight line and having yokes and another leg completing the magnetic circuit through said winding leg, and two windings about and movable along said winding leg toward and from each other, of two arms pivoted at opposite sides of said winding leg, said arms being rigidly attached to said windings to positively guide the same.

5. In a constant current electrical apparatus, the combination with a core having a winding leg the axis of which is substantially a straight line and substantially vertical and having yokes and another leg completing the magnetic circuit through said winding leg, and two windings about and movable along said winding leg toward and from each other, of two pivoted arms rigidly attached to said windings to positively guide the same, a lever pivoted between its ends, and coupling members coupling said arms to opposite ends of said lever.

6. In a constant current electrical apparatus, the combination with a magnetic core having a winding leg and cooperating members forming a window, of a plurality of windings surrounding the winding leg which traverse the window, one of said windings being adapted for movement along said leg, means rigidly secured to said core exteriorly of said window, and a mechanically counter-balanced pivoted device swung from said means for supporting said movable winding.

7. In a constant current electrical apparatus, the combination with a magnetic core having a winding leg and cooperating members forming a window, of a plurality of windings surrounding the winding leg

which traverse the window, one of said windings being adapted for movement along said leg, means rigidly secured to said core exteriorly of said window, and a mechanically counter-balanced pivoted device axially supported at a plurality of points spaced apart, said device engaging with the sides of said movable winding.

8. In a constant current transformer, relatively movable primary and secondary coils, and means for pivotally mounting said coils to constrain them to move in parallelism.

9. In a constant-current transformer having relatively movable coils, mounting means for the relatively movable coils constraining their pivotal movement in parallel planes.

10. In a constant-current transformer, the combination with a core member having a leg portion, of two flat coils loosely surrounding said leg portion, said coils being pivotally mounted for rotation about parallel axes disposed on opposite sides of said core member, said axes being perpendicular to a plane passing through the longitudinal axis of said core member.

11. In a constant-current transformer, the combination with a core member having a leg portion, of two flat coils loosely surrounding said leg portion, said coils being pivotally mounted for rotation about parallel axes disposed on opposite sides of said core member, said axes being perpendicular to a plane passing through the longitudinal axis of said core member, and a linkage interconnecting said coils whereby their

planes are at all times maintained substantially parallel.

12. In a constant-current transformer, the combination with a core member provided with a vertically disposed leg member, of two flat coils loosely encircling said leg member and mounted for movement about parallel horizontal axes disposed on opposite sides of said leg member, whereby said coils may move relatively to each other.

13. In a constant-current transformer, the combination with a core member provided with a vertically disposed leg member, of two flat coils loosely encircling said leg member and mounted for movement about parallel horizontal axes disposed on opposite sides of said leg member, whereby said coils may move relatively to each other, and a linkage interconnecting said coils, whereby their planes are at all times maintained substantially parallel.

14. In a constant-current transformer, the combination with a magnetic core provided with a vertically disposed leg member, of primary and secondary windings in the form of flat coils loosely surrounding said leg member and pivoted for rotation about horizontally disposed axes on opposite sides of said leg member, respectively, a centrally pivoted lever mounted above said core member, and links connecting the respective ends of said lever with the bodily movable coil portion therebeneath.

In witness whereof, I have hereunto set my hand this 14th day of November, 1917.

LYMAN ARNOLD.
